(57) **CLAIM**

We claim the ornamental design for a combined television, rollable display, and speaker drawer, as shown and described.

DESCRIPTION

FIG. 1 is a front perspective view of a combined television, rollable display, and speaker drawer showing our new design;

(Continued)

FIG. 2 is a rear perspective view thereof;
FIG. 3 is a front elevation view thereof;
FIG. 4 is a rear elevation view thereof;
FIG. 5 is a left-side elevation view thereof;
FIG. 6 is a right-side elevation view thereof;
FIG. 7 is a top plan view thereof;
FIG. 8 is a bottom plan view thereof;
FIG. 9 is a perspective view thereof, including an enlarged detail view of the portion encircled by dot-dot-dash lines therein;
FIG. 10 is a perspective view of the combined television, rollable display, and speaker drawer of FIG. 1, shown with the speaker drawer partially opened;
FIG. 11 is a front elevation view thereof;
FIG. 12 is a rear elevation view thereof;
FIG. 13 is a left-side elevation view thereof;
FIG. 14 is a right-side elevation view thereof;
FIG. 15 is a top plan view thereof;
FIG. 16 is a bottom plan view thereof;
FIG. 17 is a perspective view thereof, including an enlarged detail view of the portion encircled by dot-dot-dash lines therein;
FIG. 18 is a perspective view of the combined television, rollable display, and speaker drawer of FIG. 1, shown with the display partially rolled up;
FIG. 19 is a front elevation view thereof;

FIG. 20 is a rear elevation view thereof;
FIG. 21 is a left-side elevation view thereof;
FIG. 22 is a right-side elevation view thereof;
FIG. 23 is a top plan view thereof;
FIG. 24 is a bottom plan view thereof;
FIG. 25 is a perspective view thereof, shown in an environment of use;
FIG. 26 is a perspective view of the combined television, rollable display, and speaker drawer of FIG. 1, shown with the display fully rolled up;
FIG. 27 is a front elevation view thereof;
FIG. 28 is a rear elevation view thereof;
FIG. 29 is a left-side elevation view thereof;
FIG. 30 is a right-side elevation view thereof;
FIG. 31 is a top plan view thereof;
FIG. 32 is a bottom plan view thereof; and,
FIG. 33 is a perspective view thereof, shown in an environment of use.
Broken lines and unshaded portions adjacent to broken lines illustrate portions of the combined television, rollable display, and speaker drawer that form no part of the claimed design. Additional broken lines in FIGS. 25 and 33 depict environmental subject matter that forms no part of the claimed design.
